PORTABLE BUILDING

Eugene Kurash, Kansas City, Mo., assignor to Electric
Utilities Corporation, Kansas City, Mo., a corporation
of Missouri

Filed Mar. 16, 1966, Ser. No. 1,488

Term of patent 14 years

(Cl. D13—1)

Fig. 1.

Fig. 2.

FIG. 1 is a front and side perspective view of a portable building, showing my new design;

FIG. 2 is a top plan view thereof;

FIG. 3 is a front, elevational view thereof;

FIG. 4 is a rear, elevational view thereof;

FIG. 5 is an elevational view of one side thereof; and FIG. 6 is a cross-sectional view taken along line 6—6 of FIG. 5 of the portable building.

The dominant features of the design are shown in full lines.

I claim:

The ornamental design for a portable building, as shown and described.
